ENGINE STARTER GEARING

James E. Buxton, Elmira, N. Y., assignor to Bendix Aviation Corporation, a corporation of Delaware

Application April 5, 1951, Serial No. 219,427

3 Claims. (Cl. 74—7)

1

The present invention relates to engine starter gearing, and more particularly to that type in which the engagement of the drive pinion with the engine gear is initiated by magnetic action and completed by mechanical means.

It is an object of the present invention to provide a novel starter drive of the above type which is effective and reliable in operation and simple and economical in construction.

It is another object to provide such a device in which the mechanical meshing means for the pinion operates positively but quietly and without shock.

It is another object to provide such a device in which the meshing and rotating means includes a coiled spring which serves both as a clutching means and as a mesh-enforcing means.

Further objects and advantages will be apparent from the following description taken in connection with the accompanying drawing in which:

Fig. 1 is a side elevation partly broken away and in section of a starting system constituting a preferred embodiment of the invention, the electrical elements being shown diagrammatically; and

Fig. 2 is a detail on an enlarged scale in side elevation, partly broken away and in section showing the mechanical traversing mechanism for the starting pinion.

In Fig. 1 of the drawing there is illustrated a starting motor indicated generally by the numeral 1, the armature 2 of which is shiftable axially so as to move the power shaft 3 thereof longitudinally. A spring 4 operating on a slidable plunger 5 normally maintains the armature decentered to the right with relation to the field coils 6 of the motor as illustrated. A latch 7 is arranged to restrain the plunger 5 from urging the armature into decentered position except when released by a trip 8 actuated by opening the starting switch 9.

The structure for controlling the longitudinal movement of the armature shaft is the same and operates in the same manner as that illustrated in the patent to Buxton 2,394,531, so that further description thereof is deemed unnecessary.

Pinion 11 is slidably journaled on the armature shaft 3 for movement thereon and therewith into mesh with a gear 12 of the engine to be started. Means for sliding the pinion along the armature shaft is provided comprising a screw shaft 13 fixed as indicated at 14 on the armature shaft, a control nut 15 threaded on the screw shaft, and a barrel member 16 surrounding the

15 screw shaft and control nut. The control nut 15 is provided with a radial flange 17 and a cylindrical surface 18 adjacent thereto. The pinion 11 has a driven coupling member 19 fixed thereon in any suitable manner, having a radial flange 21 and a cylindrical surface 22 similar to the surface 18 of the control nut.

A cylindrical compression and torsion spring 23 is seated at its ends on the surfaces 18 and 22 of the control nut and coupling member, and is maintained under initial endwise compression between the flanges 17 and 21 of said members by means of an internal shoulder 24 of the barrel which limits endwise movement of the control nut within the barrel, and a lock ring 25 retained in the open end of the barrel as indicated at 26 and serving as a back stop for the coupling member 19.

The barrel 16 has an inturned flange 27 which is arranged to engage the end of the screw shaft 13 to limit the meshing movement of the barrel and pinion on the armature shaft; and an anti-drift spring 28 is provided in the barrel located between the flange 27 and a shoulder 29 on the screw shaft so as to normally maintain the parts in idle position as illustrated, with the control nut in engagement with the ends of the threads of the screw shaft.

In operation, when the starting motor is energized, the mutual attraction of the armature and field causes the armature to center itself with respect to the field coils so as to move the shaft 3 to the left, thereby bringing the end of the pinion 11 to the dotted line position (A) as shown in Fig. 2 where it is in initial meshing relation with the engine gear 12. If, during this longitudinal movement of the pinion, a pinion tooth should abut against a tooth of the engine gear, the movement of the pinion is momentarily arrested, causing the spring 23 to be compressed until the torque of the armature transmitted through the threaded connection and the spring 23 indexes the pinion into proper registry with the tooth spaces of the engine gear. The spring 23 thereupon expands and propels the pinion toward meshed position. Rotation of the armature then commences and is transmitted to the screw shaft 13, which causes the control nut 15 to be further traversed to the left, moving the pinion 11 and barrel 16 by compression of spring 23 until the pinion reaches the fully meshed position indicated by the dotted line (B), whereupon the longitudinal movement of the pinion is arrested by the engagement of the barrel 55 flange 27 with the end of the screw shaft 13.

The spring 23 is then further compressed by the control nut 15, and is caused to wrap down on the cylindrical surfaces 18, 22 of the control nut and coupling member 19 so as to yieldingly couple these members together and transmit the cranking torque to the pinion.

When the engine starts, the acceleration of the pinion causes the spring 23 to move the control nut back in the barrel 16 against the shoulder 24, at which time the spring is permitted to unwrap and the pinion can overrun freely except for the small amount of friction between the end of the spring 23 and the flange 21 of the coupling member. The spring 23 is thus arranged to combine the functions of a mesh-enforcing spring, a yielding driving connection, and an overrunning clutch.

If the engine does not continue to be self-operative, as soon as the rotation of the engine gear is retarded to correspond with that of the pinion, the cranking operation will be resumed. When a successful start has been secured, the release of the starting switch 9 by the operator deenergizes the starting motor and trips the latch 7, permitting the parts to return to their normal idle positions where they are retained by the spring-pressed plunger 5.

Although but one embodiment of the invention has been shown and described in detail, it will be understood other embodiments are possible and changes may be made in the design and arrangement of the parts without departing from the spirit of the invention.

I claim:

1. Starter gearing for internal combustion engines including a longitudinally shiftable shaft, a screw shaft fixed thereon, a control nut and a driving clutch member threaded on the screw shaft having a smooth cylindrical clutch surface, a pinion slidably journaled on the power shaft, a driven clutch member fixed to the pinion having a cylindrical surface similar to that of the driving clutch member, a coiled spring seated at its ends on said cylindrical surfaces, wound in the direction to wrap down and grip the cylindrical surfaces when cramping torque is transmitted therethrough, a barrel member surrounding the clutch members limiting their separation and having a terminal flange which engages the end of the screw shaft to limit the travel of the clutch members and pinion thereon, and means for shifting the power shaft to move the pinion into and out of initial meshing engagement with a gear of the engine to be started.
2. Starter gearing as set forth in claim 1 in which the driving and driven clutch members each have a radial flange, and the clutch spring engages the flanges to yieldingly maintain the clutch members in extended relation.
3. Starter gearing as set forth in claim 2 in which the driven clutch member is slidably received in the barrel so as to compress the clutch spring when the meshing movement of the pinion is arrested.
